UNITED STATES PATENT OFFICE.

FRANCIS F. PARSONS, OF PATERSON, NEW JERSEY, ASSIGNOR TO ALFRED SCHIFFER AND HERMAN SCHIFFER, OF SAME PLACE.

MEANS FOR TRANSMITTING MOTION.

SPECIFICATION forming part of Letters Patent No. 586,563, dated July 20, 1897.

Application filed January 6, 1897. Serial No. 618,162. (No model.)

To all whom it may concern:

Be it known that I, FRANCIS F. PARSONS, a citizen of the United States, residing at Paterson, in the county of Passaic and State of New Jersey, have invented certain new and useful Improvements in Means for Transmitting Motion; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My device has for its object the creation of a lateral reciprocatory motion such as might, for instance, be utilized in causing a thread or cord to be wound on a spool or a silk warp on its warp-roll, with the understanding, of course, that mechanical means are furnished to perform the winding, as my device only creates the movement that with the proper intermediate means will carry a thread or warp laterally back and forth from one end of a spool or warp-roll of any length to the other, and while the spool or warp-roll is caused to revolve will thus give the necessary motion to any employed means, winding the thread evenly and smoothly on the said spool or roll.

In many cases of machinery a motion created by the herein-described lever system will prove very valuable. The component elements of this lever system and their method of operation with each other I shall now proceed to describe, and in so doing will call attention to the accompanying drawings, wherein like letters of reference indicate corresponding parts in the different views.

Figure 1 is a front view of my device. Fig. 2 is a side view of the lever A, referred to in the description as the "traverse-regulator," and the guide-arm B. Fig. 3 is a side view of the lever D. Fig. 4 is a section on line xx of Figs. 2 and 3; and Fig. 5 is the bolt or pin M', prolonged so as to contain any needed number of arms that can transfer the same motion as the arm N on lever D.

The lever A, referred to as the "traverse-regulator," is constructed in the following manner: Mounted in the upper part adjacent

to the bearing F, to which the regulator is pivoted by the pin F', are a pair of miter-gears C' and C², of which C' has a hand-wheel C³ attached, and C² a screw-cut rod C⁴ fittingly secured to it, said rod passing through the whole length of the regulator. This screw-cut rod C⁴ passes through a similarly screw-cut nut G, which as a consequence will move up or down according to the manipulation of the hand-wheel C³ to the right or to the left. Projecting from and forming part of the nut G is a pivot-pin G', which passes through a guiding-block B', which latter is secured in the guide-arm B, so as to have a free up-and-down motion in said guide-arm, moving consequently with the pin G'. The guide-arm B is pivoted appropriately in a bearing H and is the lever in the herein-described system which will receive the motive power at a point indicated by the circle Z in any suitable mechanical manner—as, for instance, by eccentric disks, cam combinations, &c., sufficient for explanatory purposes—that is to say, that any motion administered to this lever pushing it in the direction of arrow 1 to a second position indicated by the dotted lines and back again to its original position will meet the requirements of my invention. The guide-arm B is constructed with an oblong slot B² at one end which contains, as above stated, the guiding-block B', said nut B' kept in its position in the guide-slot B² by the disk B³ and finally by a stop-ring B⁴, secured to the end of the traverse-regulator nut-pin G' by a pin B⁵. The traverse-regulator has, furthermore, cast on it at the bottom end two short projections L' and L², between which is pivoted one end of link E, the other end of said link E being attached to the lever D, which is the lever that finally transfers the lateral reciprocatory movement to any part or parts of mechanical means that may be intermediate between the said lever D and the object recipient of the above motion.

The end of lever D, to which link E is attached, is made with a slot D' to permit a certain play to link E. The means of attachment between the two (link and lever) is by means of a pin D², two disks D³ and D⁴ on each flat side of the slot, and a cross-pin D⁵, through the end of pivot-pin D².

Lever D is pivoted in a bearing M by means of pin M', and this pin M' represents the fulcrum for lever D, around which the lateral reciprocatory movement takes place that is 5 the object of my invention.

I wish it to be understood that my invention is not limited to a single fulcrumed lever, as lever D, and that if the pin or bolt M' was prolonged to any reasonable length and 10 supported any number of arms, like the upper part N of lever D, as shown in Fig. 5, the conceptional idea remains the same, and any such multiplication of arms N N' N², &c., would constitute an infringement on my in- 15 vention. It will now be readily seen that if a motive power be applied at point Z on guide-arm B by appropriate mechanical means, thus giving a motion to guide-arm B from the full-lined illustration of the guide- 20 arm in the direction of the arrow 1 to the dotted-line representation of said arm and back again, said motion will be transmitted through traverse-regulator A to link E and finally to lever D, whose upper arm N or arms N N' N², 25 &c., attached, respectively, to the pin M' or to a prolonged pin M², will give a lateral reciprocatory movement to any mechanical means where such a movement is sought for, which was the desired object. The length of 30 the stroke back and forth is regulated by the traverse-regulator, from whence the term "traverse-regulator" applied is derived, inasmuch as it regulates the traverse movement at the end of part N of lever D. This 35 is done by manipulating hand-wheel C³, so as to move the nut G up or down. In moving it upward it is obvious the stroke will be lengthened, as it will move guide-arm B with a longer arc, with the pin attaching said guide- 40 arm to the bearing H as a center for the arc and a consequent longer radius, and when

the nut G is at the bottom of the traverse-regulator the corresponding arc will have its shortest radius and consequent shortest arc and thereon attendant shortest stroke. The 45 three bearings F, H, and M will be attached immovably to any part or parts consistent with the locality and circumstances where this lever system may be used and are, mathematically speaking, three fixed centers around 50 which this lever system moves.

What I consequently claim, and desire to secure protection for by Letters Patent of the United States, is—

1. In means for transmitting motion, the 55 combination of the following elements: two levers each pivoted to a stationary bearing, a pivot connecting said levers, means whereby said pivot can be adjusted longitudinally of said levers, a third lever, and a link connecting said third lever with one of the first-named levers, substantially as described.

2. In means for transmitting motion, the combination of the following elements: two levers each pivoted to a stationary bearing 65 and each being longitudinally slotted, a nut movable in the slot of one of said levers, a guiding-block movable in the slot of the other lever and pivoted to said nut, means for simultaneously adjusting said nut and block in 70 their respective slots, a third lever and a connection between said third lever and one of the first-mentioned levers, substantially as described and for the purposes as set forth.

In testimony that I claim the foregoing I 75 have hereunto set my hand this 23d day of December, 1896.

FRANCIS F. PARSONS.
